DESIGN FOR A GLOVE

William H. Skaine, Gloversville, N. Y., assignor to Fownes Brothers & Company, Inc., New York,
N. Y., a corporation of New York

Application March 25, 1940, Serial No. 91,219

Term of patent 7 years

To all whom it may concern:

Be it known that I, William H. Skaine, a citizen of U. S. A., residing at Gloversville, in the county of Fulton and State of New York, have invented a new, original, and ornamental Design for a Glove, of which the following is a specification, reference being had to the accompanying drawing, forming a part thereof, and which is a rear view of a glove showing my new design.

The design comprises a glove, the front of which is conventionally plain and having on the back thereof welts formed by two lines of adjacently disposed double thread stitches, said welts and stitches being arranged as shown.

I claim:

The ornamental design for a glove, as shown and described.

WILLIAM H. SKAINE.
